UNITED STATES PATENT OFFICE.

EDWARD F. BENOIT, OF NEW BEDFORD, MASSACHUSETTS.

SLIVER-CLEANER FOR FLIERS.

1,222,840.

Specification of Letters Patent. Patented Apr. 17, 1917.

Application filed May 31, 1916. Serial No. 100,918.

To all whom it may concern:

Be it known that I, EDWARD F. BENOIT, a citizen of the United States, and resident of New Bedford, in the county of Bristol and State of Massachusetts, have invented certain new and useful Improvements in Sliver-Cleaners for Fliers, of which the following is a specification.

The present invention relates to new and useful improvements in fliers used in slubbing machines in cotton mills and the like, the primary object of my invention being to provide an improved type of scraper for removing bunches, dirt and the like from the sliver.

Another object of my invention is to provide a device of the character described which may be attached to the standard type of flier now in common usage without materially altering the structure of the flier.

It is well known to those skilled in the art that in the fliers now in use if the attendant is not careful and conscientious in his work, bunches will be wound onto the spool thus causing waste and loss of time. It is also understood that not only do bunches occur in the sliver but double-roving is often permitted to be wound upon the spool together with the perfect sliver. This causes flaws in the knitted structure or the fabric when manufactured, thereby causing an imperfect product.

It is therefore, a further object of my invention to provide a scraper for attachment to a flier for removing bunches, double-roving, and particles of shells or dirt which may exist in the sliver.

Other objects and advantages to be derived from the use of my improved sliver cleaner will appear from the following detail description and the claim, taken with an inspection of the accompanying drawing, in which:

Figure 1 is a side elevational view of the preferred form of sliver cleaner of my invention, the same being shown applied to a flier;

Fig. 2 is an enlarged perspective view of the device of my invention attached;

Fig. 3 is a fragmental side elevational view of a modified form of my invention;

Fig. 4 is an enlarged detached perspective view showing the scraper of the modified form of my invention illustrated in Fig. 3;

55 and

Fig. 5 is a side elevational view of a further modified form of my invention.

Referring more particularly to the drawing, wherein similar characters of reference designate like and corresponding parts throughout the various views, 1 designates a spool commonly used in slubbing machines and 2 designates in its entirety the flier. The flier 2 is provided with the usual arms 3 and 4 and a head 5. The head 5 is hollow and is provided with a laterally arranged opening 6. The arm 4 is hollow and provided with an enlargement 7 at the upper end thereof, said arm being provided with the usual slot in the outer portion thereof, 65 for insertion of the sliver, said sliver being designated 8.

The device of the preferred form of my invention includes a plate 9 formed with a base portion 10 recessed as at 11 to engage 75 about the head 5 as best shown in Fig. 1, the body 9 being provided with a diagonal slot 12 opening at the upper edge of said body and being provided with an enlargement 13 at the inner end thereof. The base 20 portion 10 is adapted to be soldered or otherwise secured to the flier 2, the plate 9 extending over the open end of the enlargement 7 as best shown in Fig. 1.

In using this form of my invention the 85 sliver 8 is to be threaded through the head 5 of the flier and brought out through the opening 6. The sliver is then engaged in the tubular arm 4 through the usual slot provided therefor, said sliver passing through 90 the opening 13 in the plate 9. The usual means may be provided for directing the sliver onto the spool 1. It will be seen that as the sliver passes through the plate 9 said plate will remove bunches and particles of 95 shell or dirt from the sliver.

Referring specifically to the modified form of my invention shown in Figs. 3 and 4 the usual spool is provided and has been given the same designation as the spool 1, as are 100 the arms 3 and 4 of the flier and the head 5 thereof. The head in this instance is also provided with the opening 6 the same being shown in dotted lines in Fig. 3. In this form of my invention, however, I provide a 105 semi-circular plate 14 provided with a slot 15 therein, said slot opening at the upper marginal edge of the plate. The inner end of the slot is provided with an enlarged portion forming an opening 16. The sliver has 110

also been designated 8 in this form of my invention and is shown arranged through the opening 6 and the opening 16 in Fig. 3. The operation of this form of my invention 5 is practically identical with the form of my invention shown in Fig. 1, the location of the scraper being, of course, slightly different. The scraper 14 of the modified form of my invention, shown in Figs. 3 and 4 is secured 10 to the head 5 of the flier by soldering or otherwise.

Referring specifically to the modified form of my invention shown in Fig. 5 I have provided in this form the usual head 17, arms 15 18 and 19 associated with the usual spool 20. However, in this form of my invention the head 17 is slotted as at 21 to receive the sliver 22. A tongue portion 23 is formed by said slot, said tongue adapted to frictionally engage the sliver as the same passes 20 therebeneath for removing particles of dirt or the like therefrom. This form of my invention operates similarly to the previously described forms.

25 Of course, if desired the forms of my invention illustrated in Figs. 1 to 4 may be combined in a single structure. In the form shown in Fig. 5 the flier is to be manufactured with the slot formed therein, or said 30 slot may be formed in the head after manufacture.

I desire to lay particular stress upon the simplicity of all of the forms of my inven-

tion as well as the scope of their application. It will be readily understood by those skilled 35 in the art that the devices of my invention and the modified forms may be applied to fliers of various constructions and types without departing from the spirit of my invention.

40 From the above description taken in connection with the accompanying drawing, it is thought that a clear and comprehensive understanding of the construction, operation and advantages of my invention may be had, 45 and while I have shown and described the device as embodying a specific structure, I desire that it be understood that such changes may be made in said structure as do not depart from the spirit and scope of 50 the invention as claimed.

Having thus fully described my invention, what I claim as new and desire to secure by Letters Patent, is:—

The combination with a flier, said flier 55 having a head provided with an outlet opening to accommodate a sliver, of a scraping member adapted for association with said head, said member being formed of a sheet of metal arcuate in cross section and provided with a slot terminating in an enlarged portion forming an opening for registration with the opening in the head.

In testimony whereof, I affix my signature hereto.

EDWARD F. BENOIT.
